UNITED STATES PATENT OFFICE

WALTER H. COTTON, OF CHICAGO, ILLINOIS, ASSIGNOR TO UNION DRAFT GEAR COMPANY, OF CHICAGO, ILLINOIS, A CORPORATION OF DELAWARE

DRAFT GEAR

Application filed September 17, 1923. Serial No. 663,083.

The invention relates to draft gears for railway cars, its objects being to secure a high degree of efficiency and durability.

A preferred embodiment of the invention is hereinafter described and is illustrated in the accompanying drawings, in which—

Fig. 1 is a central plan section of the gear, details of portions of the car to which it is applied being shown in plan;

Fig. 2 is a central longitudinal vertical section of the gear, the rear end of a coupler enclosing it being shown in detail side elevation;

Fig. 3 is a plan section of the gear under compression, the interior elements of the gear and details of parts of the car being shown in plan;

Fig. 4 is a transverse sectional view on the line 4—4 of Fig. 3; and

Figs. 5, 6 and 7 are details in perspective of elements of the gear.

A pair of draft or center sills of a railway car are shown at 10, 10; a pair of draft lugs at 11, 11, and of buffing lugs at 12, 12. The butt of the coupler is designated 13 and the coupler extension or yoke, 14. All of these parts are of any preferred construction and are not involved in the invention.

The improved draft gear comprises a chambered follower 15 having top and bottom walls 16, 17 and side walls 18, 19; and a follower 20 which is preferably in the form of a plate. Adjacent faces of the two followers are spaced apart a suitable distance to permit, and limit, the desired maximum compression of the gear.

The principal frictional elements of the gear comprise two groups of flat, intercalating plates, one upon each side of the axis of the gear, and each group comprising a set of plates 21 which normally extend from or substantially from the inner end face of the follower 15, toward the other follower; the other set, 22, extending normally approximately from the follower 20 well into the chamber of the follower 15. The outer plate of each group is in slidable engagement with a side wall of the follower 15.

Interposed between the two groups of plates are a set of wedging elements and

shoes. The central wedging element 23 bears against the follower 20 and, as is plainly shown in Fig. 7, is provided with two sets of wedging faces as 24, 25 and 26, 27. The wedging faces 24 and 26 are formed on the upper portion of the wedge element and cooperate with a pair of shoes, one of which is shown detached from the gear in Fig. 6. The wedging faces 25 and 27 are formed on the lower portion of the wedge element and cooperate with a similar pair of shoes. Each of the four shoes, as 28, is provided with wedging faces 29, 30, cooperating with a pair of the wedging faces of the wedge element. The outer face of each of the shoes is flat.

Interposed between the shoes 28 and each group of friction plates is a wedging friction plate 31, the outer face of which is parallel to the axis of the gear, the inner face taking the form of a long inclined plane.

The spring elements of the gear are helical in form and are located on the horizontal median line of the gear, the various wedging and friction elements of the gear being either bifurcated or spaced apart for their accommodation. To this end the wedging element 23 comprises a base block which bears against the follower 20 and upper and lower projecting arms which carry the wedge faces; the cooperating shoes 28 are four in number and are arranged two above and two below the spring chamber. The plates 31 have their thicker ends against the end wall of the follower 15 and are bifurcated, as are also all of the friction plates of the two groups.

The springs are shown as five in number. The central spring 32 is located on the axis of the gear and reacts between the end wall of the follower 15 and a spring seat 33, which extends upwardly and downwardly and bears against shoulders 34 formed on the shoes 28 and is slotted from its ends as plainly shown in Fig. 4 to provide clearance for the two arms of the wedging element 23. Two of the springs 35, 36, are located at one side of the axis of the gear and react between the plate 37 seated at the inner end of the slot in one of the plates 31 and the several friction plates 21. The other two springs, 38, 39, are located on the opposite side of the axis of the gear

and are similarly associated with the other plate 31 and the friction plates 21.

At the opposite end of the gear the springs 35 to 39 are seated against a bar 40 which projects through the slots of the wedging element 23 and the several plates 22, and is engaged by all of these elements.

On the application of buffing stresses the follower 15 is moved backward, carrying with it the plates 21 and 31. The shoes 28 tend to move backwardly under the influence of the frictional engagement of the plates 31, such movement however being resisted by the several wedging faces of the element 23 and under the influence of these wedges and of the long inclined faces of the plates 31 the latter plates are pressed outwardly, compressing the two groups of friction plates against the side walls of the follower. The plates 21 are moved inwardly by the follower 15 and slide, under heavy friction, between the plates 22. The latter plates, which normally are preferably slightly spaced from the follower 20 are carried backward by the friction until they make contact with this follower. All of the springs are put under compression.

When pressure is relieved, the parts of the gear are restored to normal position by the expansion of the springs.

Under stresses of draft the action is the same but in the reverse direction, the elements which in buffing have been carried backward remaining stationary and the elements which in buffing have remained substantially stationary being carried forward.

Various detailed changes in the form and arrangement of the parts may be made within the scope of the invention.

I claim:

1. In a draft gear, in combination, a pair of opposed followers, two sets of cooperating wedging and friction elements interposed between the followers, said friction elements being bifurcated to provide a spring chamber located on the horizontal median portion of the gear, means for resisting the wedging action of said elements, and a series of springs housed within the chamber and reacting between the named cooperating elements.

2. In a draft gear, in combination, a pair of followers, one of which is chambered, a group of bifurcated intercalating friction plates within said chambered follower, means for relatively advancing the plates, lateral pressure creating means for forcing said plates into frictional contact with each other and with said chambered follower, and a spring housed between the arms of the plates for resisting such movement.

3. In a draft gear, in combination, a pair of followers, a group of two sets of friction plates at each side of the gear between said followers, one set of said plates being associated with one of said followers and the

other with the other follower, a bifurcated wedging element between said groups of plates, friction shoes, having wedging faces, cooperating respectively with the two arms of the wedging element for creating lateral pressure on said plates during the compression of said gear, means for resisting said lateral pressure, and a spring located between the arms of the wedging element for resisting longitudinal movement of the named parts.

4. In a draft gear, in combination, a chambered follower, a follower opposed thereto, two groups of intercalating bifurcated friction plates on opposite sides of the axis of the gear, the sets of plates constituting each group co-operating with different followers, a central wedging element cooperating with one of the followers, friction shoes having wedging faces cooperating with the wedging element, a tapering plate interposed between the shoes and each group of friction plates, and resilient means for resisting compression of said gear and for restoring the parts to normal position after compression.

5. In a draft gear, in combination, a chambered follower, a follower opposed thereto, two groups of intercalating friction plates on opposite sides of the axis of the gear, the sets of plates constituting each group co-operating with different followers, a central wedging element cooperating with one of the followers, friction shoes having wedging faces cooperating with the wedging element, and a tapering plate interposed between the shoes and each group of friction plates, all of the named parts being bifurcated or spaced to provide a spring pocket on the horizontal median portion of the gear, and springs housed within such pocket for resisting the relative longitudinal movement of cooperating parts.

6. In a friction shock absorbing mechanism, the combination with a container having interior longitudinally extending friction surfaces and an integral inner end wall, of a plurality of relatively stationary bifurcated friction plates within said container and extending from the outer to the inner end thereof and bearing loosely on said inner end wall of the container; a plurality of relatively movable bifurcated friction plates cooperable with the friction surfaces of the container and said stationary plates; centrally disposed pressure-transmitting and lateral pressure-creating means cooperable with said friction plates; and a spring resistance within the space formed by the furcations of said plates.

7. In a draft gear, a pair of followers, a group of two sets of intercalated plates at each side of said gear between said followers and adapted to be engaged by said followers upon compression of the gear, cooperating wedge elements between said plates for creating lateral pressure on the central portion of said plates adjacent to the transverse axis

thereof, means for resisting said pressure, a plurality of springs for resisting the inward movement of the parts during compression and for restoring the parts to normal position after compression, said springs being arranged in a row and each spring extending longitudinally of the gear, and said row extending transversely thereof.
